UNITED STATES PATENT OFFICE.

EDGAR T. BOND, OF CHICAGO, ILLINOIS.

FOLDABLE CRATE.

1,127,582.

Specification of Letters Patent.

Patented Feb. 9, 1915.

Application filed February 19, 1914. Serial No. 819,703.

To all whom it may concern:

Be it known that I, EDGAR T. BOND, a citizen of the United States, residing at Chicago, in the county of Cook and State of Illinois, have invented certain new and useful Improvements in Foldable Crates, of which the following is a specification, reference being had to the accompanying drawings, forming a part hereof.

10 This invention relates to foldable crates or receptacles designed more especially for transportation and storage purposes, but which are adapted for use and can be used for other purposes.

15 The objects of the invention are: To construct a crate that will be light and at the same time strong, durable and easily handled and manipulated in use; to enable the crate or receptacle to be unfolded or set up 20 for use and folded to occupy but little space, and this without any trouble or inconvenience, and have both operations readily and quickly performed; to form the top and sides of the crate or receptacle of bars or 25 rods of metal or other suitable material having sufficient rigidity to furnish the necessary strength for the crate or receptacle when unfolded or set up; to form two opposite sides of the crate or receptacle from 30 two corner posts and cross-bars, the corner posts each pivoted at its lower end to fold downwardly and inwardly, and forming the other two opposite sides of the crate or receptacle from two corner posts and cross- 35 bars, the corner posts each pivoted at its lower end to fold downwardly and inwardly, the pivots for one set of corner posts being in a higher plane than the pivots of the other set of corner posts; to form each corner post 40 of two members separated or spaced apart to furnish a longitudinal opening between the members, into which opening is entered and secured the ends of the cross-rods or bars for the sides of the crate or receptacle; to fur- 45 nish a top movably connected with the sides of the crate or receptacle so as to be raised and lowered with the unfolding and folding of the crate or receptacle; to furnish the top with a small opening and a closure therefor 50 for giving access to the interior of the crate or receptacle when in use without opening or removing the top as a whole; to furnish additional braces when required, for maintaining the crate or receptacle in its unfolded

operative condition; and to improve generally the construction, arrangement and operation of the several parts entering into the formation of the crate or receptacle as a whole.

The invention consists in the features of construction and combinations of parts hereinafter described and claimed.

In the drawings: Figure 1 is a top or plan view showing the crate or receptacle in its unfolded or raised position; Fig. 2, a side elevation, partly broken away, of the crate or receptacle in its unfolded or raised position; Fig. 3, a sectional elevation of the crate or receptacle in its unfolded or raised position on line 3—3 of Fig. 1, showing the top or cover partly open; Fig. 4, a side elevation, partly broken away as in Fig. 2, showing the crate or receptacle in the act of being folded; Fig. 5, a detail, partly in section, showing the hinge or connection for the swinging section of the cover or closure; Fig. 6, a top or plan view of the hinge or connection of Fig. 5, and Fig. 7, an enlarged detail on line 7—7 of Fig. 2, partly in section, of one corner of the crate or receptacle, showing the form and arrangement of the corner posts.

In the drawings similar reference numerals indicate corresponding parts.

The crate or receptacle, in the construction shown, has a bottom 1, to the upper face of which at the edges on two sides are secured cross-pieces or strips 2 and 3, and at the middle a cross-piece 4, and to the edges of the other two sides cross-pieces 5, corresponding to the cross-pieces 2 and 3. These cross-pieces or strips are for the purpose of furnishing a mounting for the corner posts and to give greater rigidity to the bottom, where thin material is used, but they could be dispensed with if the bottom was made of sufficiently thick material.

At each of the four corners of the crate or receptacle is a post or standard 6, formed as shown of two members or sections separated apart so as to leave a space or opening 7 between the members or sections. Each post or standard is of a tubular shape as shown, but could be of other shape and either hollow or solid, as may be desired. At each corner of the crate or receptacle, diagonally to each corner post 6, is a post 8, also formed, as shown, of two members or

sections separated apart so as to leave a space or opening 9 between the members or sections; and these posts or standards 8 can be of a tubular shape, as shown, or of some other shape, and either hollow or solid.

Each corner post 6 and 8 has entered into and secured in its lower end a stem 10 having an eye 11, which enters a space between two eyes 12 on stems 13, entered into the cross-strips or pieces 2 and 3 and secured therein in the construction and arrangement shown. These eyes 11 and 12 furnish the pivotal point for the posts or standards 6 and 8 to be folded downwardly and inwardly to occupy a horizontal position and to be unfolded and raised to occupy a vertical position. The pivot or hinge for each post or standard 6 is completed by a rod or wire 14, extending as shown across the crate or receptacle and passing through the eyes 11 and 12; and the pivot or hinge for each post or standard 8 is completed by a rod or wire 15 extending as shown across the crate or receptacle at right angle to the rod or wire 14 and passing through the eyes 11 and 12 of each post or standard 8, the rod or wire 14 passing through the eyes 11 and 12 of each post or standard 6. It is to be noted that the rod or wire 14 furnishing the pivot for the posts 6 is in a higher plane than the rod or wire 15 furnishing the pivot for the posts 8, by which arrangement the posts or standards 8 can be turned down into a horizontal plane for the posts or standards 6 to overlie them when turned down, which enables the crate or receptacle to be closely folded when desired or required.

The construction and arrangement shown has a middle post or standard 16 on each side, which can be similar in construction to the posts or standards 6 and 8, or can be a single member as shown, and each post or standard 16 is pivotally mounted at its lower end by eyes 11 and 12 and a rod or wire 14 or 15 so as to be folded and unfolded with the posts or standards 6 and 8 in the operation of the crate.

Two opposite sides of the crate or receptacle are each formed of rods or bars 17 passing through the corner posts or standards 6 and 16 or adjacent to the midway post or standard 16, and secured at their ends in the space or opening 7 of the posts or standards by split keys 18 passing through the rods or bars and the posts or standards 6 and 16 in the construction shown; but the rods or bars 17 could be otherwise fastened to the posts or standards. The other two opposite sides of the crate or receptacle are each formed of rods or bars 19 passing through the corner posts or standards 8 and 16 and secured at their ends in the space or opening 9 of the posts or standards by split keys 20, pass-

ing through the rods or bars and the posts or standards 8 and 16, in the construction shown; but the rods or bars 19 could be otherwise secured to the posts or standards.

The support for the cover of the crate or receptacle, in the construction and arrangement shown, consists of bars or rods 21 for two sides of the support and bars or rods 22 for the other two sides of the support, with the bars or rods 21 as shown underlying the bars or rods 22. These bars or rods 21 and 22 form the support by means of which the cover proper as a whole is held in place and are attached respectively to the corner and middle posts or uprights 6 and 16 and 8 and 16 by split keys 18 and 20, as shown, but they could be otherwise attached to the posts. The frame for the cover is formed on two sides by bars or rods 23, which may be wire or other suitable material spaced 85 apart to receive in the space between them the posts or uprights 8 on two sides of the crate, and on the other two sides by bars or rods 24, which may also be wire or other suitable material, spaced apart to receive 90 in the space between them the posts or uprights 6 on two sides of the crate, and the frame is completed by central bars or rods 25 and 25^a, also of wire or other suitable material spaced apart, the space between the bars or rods receiving the middle posts 16 on two sides of the crate and the space between the bars or rods 25^a receiving the posts or uprights 16 on the other two sides of the crate. As shown, the bars or rods 23 and 25^a are crossed by the bars or rods 24 and 25, and these bars or rods 23, 24, 25 and 25^a are located below the bars or rods 21 and 22, the bars or rods 21 overlying the bars or rods 24 and 25 and the bars or rods 22 overlying the bars or rods 23 and 25^a, with the posts or uprights 8 free to move or swing in the space between the bars or rods 23, and the posts or uprights 6 free to move or swing in the space between the bars or rods 24, permitting the supporting bars or rods 21 and 22 to be carried up and down with the posts or uprights 6 and 8 to raise and lower the cover as a whole,—the upward movement of the posts or uprights 110 6 and 8 raising the cover and the downward movement of the posts or uprights lowering the cover.

The cover proper is made in four sections or quarters. One section has side bars or rods 26 and 27 and its companion section has side bars or rods 28 and 29, with cross-wires 30 between the side bars or rods 26 and 27 and between the side bars or rods 28 and 29, such cross-wires 30 extending from the side 125 bar or rod 26 to the side bar or rod 29 and through the bars or rods 27 and 28 in the form shown for one-half of the cover, but, if desired, these cross-wires 30 need not extend beyond the bars or rods 27 and 28 and 130

could terminate at said bars or rods. Each section has wires 31 extending over and cross wise to the wires 30 and forming with the wires 30 a grating. The wires 31 are 5 entered into side bars or rods 32 located above and crossing the wires 26, 27, 28 and 29, and extending across and over the frame bars or rods 23 and 25^a for the outer side bar or rod 32, and terminating at the bars 10 or rods 23 for the inner side bar or rod, which completes one-half of the cover; and it is to be understood that the side bars or rods 26, 27, 28, 29 and 32 can be heavy wire or other suitable material. The other half 15 section of the cover has an upper portion formed of quarter sections; one quarter section consists of side bars 33 with cross-wires 34 extending from side bar to side bar; the other quarter section consists of side bars 20 35 with cross-wires 36 extending from side bar to side bar. The side bars 33 and 35 are joined or connected at their inner ends by a joint or hinge so that either quarter section can be raised and lowered—one section being shown raised in Fig. 3 so as to 25 permit the under quarter section to be raised for access to the interior of the crate. The half section is completed by under quarter sections; and each under quarter 30 section consists of side bars 37 in right angle relation to the side bars 33 and 35, with cross-wires 38 extending from side bar to side bars for the cross-wires 38 to form with the cross-wires 34 and 36 a grating. The 35 side bars 37 are pivotally mounted on a wire 39 common to all of the side bars 38, and furnishing a pivot on which each under quarter section of the cover can be raised when the companion upper quarter section 40 is raised as shown in Fig. 3, where an upper and an under quarter section are in raised position. The side bars 33 and 35 can be tubes, and their inner ends are joined or hinged one to the other by a joint or hinge 45 which, as shown in Figs. 5 and 6, consists of a member having a stem or pin 40 entered into the end of the side bar tube 35, and secured therein by rivets 41, or otherwise. The projected end of the stem or pin 40 has 50 a slotted head 42 furnishing ears through which passes a pin or pivot 43, which also passes through an ear 44 entered into the slot of the head 42, and this ear 44 is on the projected end of a stem or pin 45, entered 55 into the end of the side bar tube 33, and secured therein by rivets 46 or otherwise.

The construction shown has on two opposite sides of the crate a diagonal brace rod 47 and each brace rod at its upper end 60 has an eye or loop 48, which is entered onto a pin 49, projecting from the outer end of the upper bar or rod 19 and at its lower end has an eye or loop 50 which is entered onto a pin 51 projecting from the end of the pivot rod 15; and the eyes or loops 48 and 50 can

be held against slipping from the pins 49 and 51 by a wire winding or in some other suitable manner. These brace rods or bars 47 serve to stiffen and strengthen the crate and also furnish additional means for holding the corner posts 8 upright when the crate is in use or unfolded. The other two opposite sides of the crate also have diagonal brace rods 52, and each brace rod 52 at its upper end has an eye or loop 53, which is 70 entered onto a pin 54, projecting from the outer end of the upper cross-bar or rod 17, and at its lower end has an eye or loop 55, which is entered onto a pin 56 projecting from the end of the pivot rod 14, and the 80 eyes or loops 53 and 55 can be held from slipping off the pins 54 and 56 by a wire winding or otherwise. These brace rods or bars 52 serve to stiffen and strengthen the crate, and also furnish additional means for 85 holding the corner posts 6 upright when the crate is in use or unfolded.

Instead of employing diagonal brace rods or bars, corner brace rods or bars can be used, or where great strength and rigidity 90 is wanted both the diagonal brace rods or bars and the corner brace rods or bars can be used. The corner brace rods or bars 57 can be made of metal tubing or other suitable material, and each rod or bar 57 has 95 at its lower end an eye or loop 58 adapted to be entered on a pin 51 projecting from the outer end of the pivot rod 15, or on a pin 56 projecting from the outer end of the pivot rod 14, as may be desired. The upper 100 end of each brace rod or bar 57 is connected with the post 6 or the post 8 by a yoke shaped connection 59, one member 60 of which is entered into the upper end of the brace rod or bar 57 and the other member 61 105 of which is entered into the upper end of a post 6 or a post 8, or if desired a brace rod or bar 57 may be provided for both corner posts 6 and 8; but for ordinary use such brace rod or bar need be applied to the corner posts 6 or to the corner posts 8 only. As shown in Fig. 1, the brace rods or bars 57 are applied to two of the corner posts 8, and as shown in Fig. 2 they are applied to two of the corner posts 6, but they can be applied to all of the corner posts 6 or corner posts 8 if required or necessary to obtain the proper strength and rigidity for the crate when in use or unfolded. It will be understood that the brace rods or bars 47 and 52, 110 or the brace rods or bars 57, are applied after the crate is raised or unfolded, and are removed when the crate is to be folded. The brace rods or bars are held on the pins by locking or winding wires 62 (see Fig. 2), 115 one end of a wire 62 being attached to the eye of a split key and the other end wound around the pin, in such manner as to prevent the eye or loop of the brace rod or bar from slipping off the pin. The cross-wires 120

forming the grating of the cover can be held in place by wire windings 63, as shown in Fig. 2, or in any other suitable manner.

The cover is raised and lowered with the 5 raising and lowering of the sides of the crate; and in raising and lowering the sides of the crate the corner posts 6 are free to move in the space between the border wires or rods 24 of the cover, and the posts 8 are 10 free to move in the space between the border wires 23 of the cover, and with the up and down movement of the corner posts the frame rods or bars 21 and 22 supporting the cover move up and down with the corner posts raising and lowering the cover.

The crate is folded by swinging the corner posts 6 downward and inward on the pivot rods 14, and swinging the corner posts 8 downward and inward on the pivot rods 15, bringing the sides of the crate into a 20 folded position as shown in Fig. 4; and in folding the crate the brace rods or bars are removed. The crate is unfolded by swinging the corner posts 6 and 8 upward into a 25 vertical position on the pivot rods 14 and 15, and after the sides of the crate are raised into a vertical position the brace rods or bars are applied as hereinbefore described. The 30 crate can be filled and emptied through the cover, by raising one or more quarter sections of the cover to obtain access to the interior of the crate, to do which it is only necessary to remove the supporting side rods of the cover. The cover, instead of being 35 movably held, could be a removable cover if so desired.

The advantages pertaining to the crate of the present invention are apparent and need 40 not be described in detail. Suffice it to say that the crate or receptacle can be readily and quickly unfolded and folded, is very 45 strong and durable, and, at the same time, light and easily handled, and when folded can be stored away and occupy but a small space in a room or other storing place.

It is not the intention to limit, restrict, restrain or confine the parts entering into the present invention for sole use in foldable crates, and under the word "crate" is 50 included coops for chickens, crates for the transportation of berries, vegetables, and other commodities, receptacles, carrying cases for eggs, folding boxes, cases or crates for the delivery of packages or bundles 55 commonly put up in grocery stores, meat markets, and other retail stores, and other articles in any general merchandise line of business, and for commercial use in the delivery of packages to customers, patrons and 60 consumers.

The gist of the present invention is in the construction and arrangement of the corner posts and foldable sides of the crate, so as to fold downwardly and inwardly and to be 65 raised into a vertical position; in the spe-

cial construction and mounting of the cover to be raised and lowered with the raising and lowering of the sides of the crate; in making the cover in hinged sections; and in the bracing of the sides of the crate when 70 raised.

What I claim as new and desire to secure by Letters Patent is:

1. In a foldable crate, the combination of a bottom, a top, eight corner posts, two for 75 each corner of the crate, each corner post pivotally mounted at its lower end adjacent to the bottom of the crate to fold downwardly and inwardly and to be raised into a vertical position, and each corner post 80 consisting of two members spaced apart, and a plurality of cross-bars for each two companion corner posts with the ends of the bars entered into and secured in the space between the members of the posts,— 85 the eight corner posts and the four series of cross-bars forming the four sides of the crate, substantially as described.

2. In a foldable crate, the combination of a bottom, eight corner posts, two for each 90 corner of the crate, each corner post pivotally mounted at its lower end adjacent to the bottom of the crate to fold downwardly and inwardly and to be raised into a vertical position, and each corner post 95 consisting of two members spaced apart, a midway post for each side of the crate, each midway post pivotally mounted at its lower end adjacent to the bottom of the crate to fold downwardly and inwardly and to be raised 100 into a vertical position coincident with the folding and raising of the corner posts, and a plurality of cross-bars for each two companion posts and secured to the corner posts and the midway side post, the eight corner 105 posts, the four midway side posts and the four series of cross-bars forming the four sides of the crate, substantially as described.

3. In a foldable crate, the combination of a bottom, eight corner posts, two for each 110 corner of the crate, each corner post pivotally mounted at its lower end adjacent to the bottom and downwardly and inwardly foldable and adapted to be raised into a vertical position, and each corner post consisting of two members spaced apart, a plurality of cross-bars for each two companion corner posts with the ends of the bars entered into and secured in the space between the members of the posts,— the eight corner 115 posts and the four series of cross-bars forming the four sides of the crate, and exterior braces for the sides of the crate, substantially as described.

4. In a foldable crate, a cover consisting 125 of supporting side rods crossing each other, border side rods spaced apart on the four sides of the cover, and a sectional cover proper, each section formed of side bars and cross-wires, one set of side bars and cross- 130

wires above the other set, and the two sets of cross-wires coacting to furnish a grating, substantially as described.

5. In a foldable crate, a cover consisting of supporting cross-rod crossing each other, border side rods spaced apart on the four sides of the cover, and a sectional cover proper formed of side bars and cross-wires, one set of side bars and cross-wires above 10 the other set, the two sets of cross-wires coacting to furnish a grating, one-half of the sectional cover having hinged quarter sections adapted to be raised for access to the interior of the crate when the supporting 15 side rods are removed, substantially as described.

6. In a foldable crate, the combination of

a bottom, foldable corner posts and sides, and a top raised and lowered with the raising and lowering of the corner posts and 20 sides, said top consisting of supporting side rods crossing each other, border side rods spaced apart and receiving into the spaces the corner posts, and a sectional cover proper, each section formed of side bars and 25 cross-wires, one set of side bars and cross-wires above the other set, the two sets of cross-wires coacting to furnish a grating, substantially as described.
